UNITED STATES PATENT OFFICE.

ADOLF ZINDLER, OF BERLIN, GERMANY.

BRIQUET AND METHOD OF MAKING THE SAME.

1,000,479.

Specification of Letters Patent. Patented Aug. 15, 1911.

No Drawing.

Application filed October 29, 1908. Serial No. 460,139.

To all whom it may concern:

Be it known that I, ADOLF ZINDLER, a subject of the German Emperor, and residing at Berlin, Germany, have invented a certain new and useful Briquet and Method of Making the Same, of which the following is a specification.

The important object of the present method is to utilize the briquetting powers of heated peat and to employ them for briquetting other substances which alone cannot be made into briquets, and in accordance with the invention substances of the latter kind, such as anthracite or stone-coal, brown coal or lignite which cannot be briquetted, small coke, and the like such as coal-dross and coal-sludge, are briquetted under pressure in suitable molds after being heated with peat which is capable of briquetting. For example, 5% to 50% of coke dust and the like which is frequently of little value and which can often be employed only with difficulty can be mixed with peat and be briquetted in the manner stated, and when the percentage of bitumen in the peat is high, even more than the above amounts of coke dust and the like can be utilized. In this manner large quantities of a fuel of inferior value are converted into valuable heating material, for, owing to the addition of stone coal, coke dust and the like which have a higher calorific value than peat, the peat briquets are improved. Also the manufacture of briquets is facilitated in consequence, because the high percentage of water in the peat is diminished by mixing it with a considerably drier material which when dried in the air frequently contains 5% to 10% of water, on which account there is less water to be evaporated in the drying process which precedes the briquetting process. The heating of the peat is essential because only in this manner is the bitumen made free and capable of being used as an agglutinant. The briquetting power of peat can also be utilized for briquetting substances for smelting purposes. For ex-

ample, fine-grained ores, alone or with fluxes, and likewise iron shavings, fine-grained waste iron and the like, can be mixed with peat, coke dust being also added, and briquetted, whereby materials which can be smelted with difficulty otherwise are made suitable for smelting purposes. Also peat can be heated itself and be then mixed and briquetted with the substances which are to be briquetted. The bitumen which is liberated on account of the heat then acts as an agglutinant.

The temperature at which the heating operation is carried out can vary between 200° F. and 600° F. It is to be understood however that this process is not to be limited to any particular temperature since any heating which will be sufficient to liberate the bitumen is within the scope of this invention.

I am aware that peat has been solidified by steam-heating, grinding and subsequent steam-heating and simultaneous pressure, but in such a process no bitumen is liberated from the peat nor are non-briquetting materials mixed with it. I am also aware that it has been proposed to form briquets of fine coal and peat by compression without the employment of heat and consequently without the liberation of bitumen from the peat. Such briquets would crumble to dust immediately heat was applied to them, if not before, and be quite unusable. Owing to the bitumen being liberated from the peat when mixed with non-briquetting materials and treated according to my improved method, durable briquets are obtained capable of resisting considerable degrees of heat and enabling otherwise non-briquetting, waste materials to be efficiently used.

What I claim as my invention and desire to secure by Letters Patent is:

1. The herein described briquet composed of peat and a non-briquetting substance, such as anthracite coal or iron ore, united by the bituminous binder naturally present in the peat.

2. The method of briquetting peat and

non-briquetting materials, such as anthracite coal or iron ore, which consists in mixing the peat and non-briquetting material, heating the peat to a temperature sufficient to liberate the bituminous binding material therein, and forming the mixture into briquets.

In testimony whereof I affix my signature in the presence of two witnesses.

ADOLF ZINDLER.

Witnesses:

HENRY HASPER,
WOLDEMAR HAUPT.
